CHECK VALVE FOR WELL PUMPS

Roger M. McClure, Delaware, Okla.

Application April 5, 1940, Serial No. 328,136

1 Claim. (Cl. 103—202)

This invention relates to an oil well pump working barrel trap and cup saver, and has for the primary object the provision of a device of this character which will materially prolong the period of operation of the pump before it is necessary to make repairs thereto and thus reduce maintenance cost.

Another object of this invention is the provision of means to prevent foreign matter which may fall downwardly from above the working barrel from entering the latter as well as preventing materials such as sand, scale or the like which has been expelled from the working barrel along with fluid from returning to said working barrel and thus eliminate wear to the valves, cups and the like of the working barrel.

A further object of this invention is the provision of a packer for the stem of the pump plunger which will prevent the passing of fluid about the stem and its guide and thereby reduce to a minimum unmarketable cut oil from the well.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a vertical sectional view illustrating an oil well pump working barrel, trap and cup saver constructed in accordance with my invention.

Figure 2 is a fragmentary side elevation showing a portion of the working barrel.

Figure 3 is a sectional view taken on the line 3—3 of Figure 1.

Figure 4 is a fragmentary exploded vertical sectional view illustrating a coupler employed for detachably connecting the pump plunger stem to the sucker rod.

Figure 5 is a perspective view illustrating a check valve.

Figure 6 is a fragmentary vertical sectional view illustrating the check valve and its seat and a packer connected thereto.

Figure 7 is a sectional view taken on the line 7—7 of Figure 6.

Figure 8 is a fragmentary vertical sectional view illustrating a modification of this invention.

Figure 9 is a fragmentary side elevation, partly in section, illustrating a part of the working barrel or pump cylinder used in the modification.

Referring in detail to the drawings, the numeral 5 indicates a pump cylinder or working barrel in which is reciprocally mounted a pump plunger 6 including a stem 7, traveling valve 8, cup assembly 9 and a removable head 10. These parts are of a conventional construction. Also removably mounted in the lower end of the pump cylinder or working barrel 5 is a stand valve 11 of a conventional construction. In Figure 1 the lower end of the pump barrel or working cylinder is shown detachably connected to a conventional anchor 12.

In adapting the present invention to the pump cylinder or working barrel 5 the upper portion thereof is provided with external screw threads 13 which are spaced a selected distance below the upper end and the latter-named end is shaped or beveled to form an internal shoulder 14 on which is mounted a check valve assembly 15.

The assembly 15 includes a body 16 having a reduced neck 17 screw threaded, as shown at 18. The body and neck have aligned openings through which extends the stem 7 of the pump plunger 6. The body 16 has a shoulder 19 which rests on the seat 14 to permit the major portion of the body 16 to be confined in the pump barrel or working cylinder. The body 16 has passages 20 therethrough and which open outwardly through the end faces of the body, one of said faces providing a seat for a check valve 21 slidably mounted on the extension or neck 17 of the check valve assembly. The check valve element 21 includes a tubular portion 22 and a substantially conical-shaped portion 23 or which may be termed as a flared skirt providing a flat under face thereto to engage one of the end faces of the body 16 and act to close the passages 20.

40 A trap forming sleeve 22' has reduced internally screw threaded ends. The sleeve 22' is threaded onto the pump cylinder or working barrel and projects a limited distance thereabove. The sleeve 22' fitting onto the pump cylinder or working barrel, as shown in Figure 1, forms a trap 23' for the collection of foreign matter and which extends a selected distance below the check valve assembly 15.

50 A packer 25 is threaded on the extension 17 of the check valve assembly and has the pump plunger stem 7 extending therethrough and is located within the upper portion of the sleeve 22'. The upper end of the sleeve 22' is connected to a well casing indicated by the character 26. A coupler 27 adjustably connects the upper end

of the stem 7 of the pump plunger to a sucker rod 28. The coupler 27 includes a socketed member 29 internally screw threaded and provided at one end with an externally screw threaded extension 30 for threading into a socket 31 carried by the sucker rod 28. The coupler 27 further includes an internally screw threaded sleeve 32 acting as a lock nut. The socketed member 29 and the sleeve 32 have wrench engaging faces. The stem 7 is threaded into the socketed member 29 and has threaded thereon the sleeve 32 which when turned tightly against the socketed member 29 will prevent the latter from unthreading from the stem 7.

The packer 25 includes a shell 33, the ends of which are internally screw threaded and have threaded therein plugs 34 and 35. The plugs are provided with aligned openings to permit the stem 7 to extend therethrough and the extension 17 threads into the plug 35, as clearly shown in Figure 6, to establish a detachable connection between the check valve assembly and the packer. The body 16 and extension 17 of the check valve assembly forms a guide for the stem 7. Packing discs 36 are mounted on the stem within the shell 33 and are forced tightly against the lower plug 35 by a spring influenced follower 38 slidable on the stem within the shell 33. A coil spring 39 is interposed between the follower and the upper plug 34 to maintain the packing discs in tight engagement with the stem to prevent leakage of fluid past the stem.

As shown in Figure 8, the present invention may be assembled within a pump cylinder 40 and the latter may be connected onto a well tubing or casing 41 by a sleeve 42. In this construction it will be seen that the trap 23 is eliminated.

From the foregoing description taken in connection with the accompanying drawings, it will be seen that the check valve assembly located in the upper end of the pump cylinder or working barrel will prevent foreign matter that may fall downwardly from the well casing from entering

the pump cylinder or working barrel, such foreign matter will accumulate within the trap 23. Also, it will be seen that any foreign matter brought up with the fluid by the operation of the 5 pump plunger after passing through the check valve assembly may settle down into the trap 23 and be prevented from returning to the pump cylinder or working barrel through the arrangement of the check valve assembly, consequently 10 keeping the pump barrel or working cylinder free of foreign matter so as to eliminate undue wear thereon as well as on the cups and valves of the plunger. The packer connected to the check valve assembly will prevent fluid from following along the stem 7 and producing cut oil 15 when wear occurs to the body 16 and extension 17 of the check valve assembly.

It is believed that the foregoing description, when taken in connection with the drawings will 20 fully set forth the construction and advantages of this invention to those skilled in the art to which such a device relates, so that further detailed description will not be required.

Having thus described the invention, what I 25 claim is:

In a device of the class described, a check valve plug shaped body snugly fitted in a pump barrel and having a flange on its upper edge resting on the upper end of a section of the barrel, said body including a flat seat at its upper end and a plurality of fluid passages opening through said seat from the opposite end of said body and a central passage and a sleeve integral with the seat and aligning with the latter-named passage, said central passage and sleeve coacting to 30 slidably support a reciprocal plunger stem throughout the length of the body and sleeve, a valve element slidable on said sleeve and including a flat face to coact with the seat in closing said fluid passages, and a packing member slidably receiving the stem and threaded on the sleeve and supported against movement with the stem by said body.

ROGER M. MCCLURE.
